UNITED STATES PATENT OFFICE.

CHARLES W. REINOEHL AND BENT L. WEAVER, OF STEELTON, PENNSYLVANIA.

COMBINED TIE-PLATE AND GUARD-RAIL BRACE.

No. 909,670.

Specification of Letters Patent.

Patented Jan. 12, 1909.

Application filed April 17, 1908. Serial No. 427,687.

To all whom it may concern:

Be it known that we, CHARLES W. REINOEHL and BENT L. WEAVER, citizens of the United States, and residents of Steelton, 5 Dauphin county, State of Pennsylvania, have invented certain new and useful Improvements in a Combined Tie-Plate and Guard-Rail Brace, of which the following is a full, clear, and exact description, reference being had to the accompanying drawings.

The object of this invention is to provide a combined tie plate and guard rail brace for railroad rails, having provision whereby 15 the guard rail will be maintained in proper relation to the main rail, as will be herein-after fully described and particularly pointed out in the claims.

In the drawings:—Figure 1 is a vertical section showing the main rail, the guard rail, and our improved tie-plate and rail-brace, and showing, by dot and dash lines, the bottom of a car wheel upon the main rail. Fig. 2 is a plan view of the parts 20 shown in Fig. 1. Fig. 3 is a plan view of the blank of plate steel from which the tie plate and rail brace shown in Figs. 1 and 2 is formed. Fig. 4 is a detail in section, as on the line 4—4, of Fig. 1. Fig. 5 is a view 25 similar to Fig. 1, showing the tie plate and rail brace formed of cast metal. Fig. 6 is a plan view of the tie plate and rail brace shown in Fig. 5. Fig. 7 is a detail in section as on the line 7—7 of Fig. 5.

In Figs. 1, 2, and 4, we show our improved tie plate and rail brace formed from a blank of plate steel, the blank being shown in Fig. 5. 1 designates the main rail, 2, the guard rail adjacent thereto, and 3, the tie plate upon which the rails 1 and 2 are supported. The space between the heads 5 and 6 of the rail 1 and 2 respectively, forms the channel through which the flanges of the car wheels pass. The ends of the plate 3 extend 40 beyond the outer edges of the foot flanges 8 and 9 of the rails 1 and 2 respectively, and the extending ends of the plate 3 are provided with suitably located spike holes 10 through which spikes 11 are driven and 45 engaged with the outer edges of the foot flanges 8 and 9, as a means for securing the rails 1 and 2 and the plate 3 to the underlying tie (not shown). Formed integral with the plate 3 is the rail brace 12, which 55 rises from the plate 3 between the inner, opposite edges of the foot flanges 8 and

9, part of the foot flange 9 of the guard rail 2 being cut away, as shown. The rail brace 12 extends from the plate 3 first upwardly, as at 13, between and in engagement with the inner edges of the foot flanges 8 and 9; then laterally, as at 14, over and into engagement with the top of the foot flange 9 and the inner face of the vertical web of the guard rail 2; and then diagonally, as at 15, through the space between the rails 1 and 2, and into engagement with the under side of the head 5 and inner wall of the vertical web of the main rail 1. The diagonally extending portion 15 of the rail 70 brace 12 is provided with a stiffening rib 16.

As previously mentioned, the construction shown in Figs. 1, 2, and 4, is made from a blank of plate steel, as shown in Fig. 3, the body 3^a of which forms the tie plate 3 75 and the tongue 12^a of which, cut from the body of the blank is bent upwardly from the body 3^a to form the rail brace 12 shown in Figs. 1, 2, and 4, the central portion of the diagonally extending part 15 of the 80 brace 12 being depressed on one face and extended on the opposite face, to form the stiffening rib 16. Thus the entire combined tie plate and rail brace may be formed from a single piece of plate steel. 85

The construction just described provides a very simple and efficient combined tie plate and rail brace. During the travel of the car wheels over the main or stock rail 1, any lateral thrust of the wheel flanges against 90 the head 6 of the guard rail 2 will tend to force the upper portion of the guard rail away from the main rail, and thus tend to raise the inner edge of the foot flange 9 thereof, the outer edge of the foot flange 9 95 pivoting against the spike 11 engaged therewith. The force of this lateral thrust is taken by the diagonal portion 15 of the brace 12, the lower end of which engages the top of the inner edge of the foot flange 9, and 100 the upper end of which engages the head 5 of the rail 1; so that pressure of the wheel flange against the head 6 of the guard rail 2 tending to raise the inner edge of the foot flange 9, also tends to raise the rail 1—which, 105 of course, is held down by the weight of the car wheel and car carried thereby passing over the main rail.

In Figs. 5, 6, and 7, we have shown a casting forming our improved tie plate and rail brace. In these figures, 3^b designates the tie plate upon which the rails 1 and 2 are 110

supported, the ends of the tie plate 3^b extending beyond the outer edges of the foot flanges 8 and 9 of the rails 1 and 2, respectively. The extending ends of the tie plate 5 are provided with suitably located spike holes 10^a, through which spikes 11^a are driven and engaged with the outer edges of the foot flanges 8 and 9, as a means for securing the rails 1 and 2 and the plate 3^b to the 10 underlying tie (not shown). The end of the plate 3^b extending beyond the outer portion of the foot flange 9 of the guard rail 2, is raised to form a shoulder 17 in engagement with the outer portion of said foot flange 9. 15 Formed integral with the plate 3^b is the rail brace 12^a, which rises from the plate 3^b between the inner, opposite edges of the foot flanges 8 and 9, part of the foot flange 9 of the guard rail 2 being cut away, as shown. 20 The rail brace 12^a extends from the plate 3^b first upwardly, as at 13^a, between and in engagement with the inner edges of the foot flanges 8 and 9; then laterally, as at 14^a over and into engagement with the top of the foot 25 flange 9 and the inner face of the vertical web of the guard rail 2; and then diagonally, as at 15^a, through the space between the rails 1 and 2, and into engagement with the under side of the head 5 and inner wall of 30 the vertical web of the main rail 1. The diagonally extending portion 15^a of the rail brace 12^a is provided with a stiffening rib 16^a.

Having thus described our invention, we claim as new and desire to secure by Letters 35 Patent:—

1. The combination of a tie plate, a main rail thereon, a guard rail on said tie plate adjacent the main rail, means for engaging the outer portion of the foot flange of 40 the guard rail, means for engaging the outer portion of the foot flange of the main rail, and a rail brace rising from said plate between the foot flanges of said rails, said brace engaging the inner portion of the foot flange 45 of the guard rail, and also engaging the under side of the head of the main rail, substantially as described.

2. The combination of a tie plate, a main rail thereon, a guard rail on said tie plate 50 adjacent the main rail, means for engaging the outer portion of the foot flange of the guard rail, means for engaging the outer portion of the foot flange of the main rail, and a rail brace rising from said plate, said 55 brace extending first upwardly between the foot flanges of said rails, then laterally into engagement with the top of the foot flange of the guard rail, and then diagonally through the space between the rails and into 60 engagement with the under side of the head of the main rail, substantially as described.

3. The combination of a tie plate, a main rail thereon, a guard rail on said tie plate adjacent the main rail, means for engaging 65 the outer portion of the foot flange of the

guard rail, means for engaging the outer portion of the foot flange of the main rail, and a rail brace having a rib formed thereon rising from said plate between the foot flanges of said rails, said brace engaging 70 the inner portion of the foot flange of the guard rail, and also engaging the under side of the head of the main rail, substantially as described.

4. The combination of a tie plate, a main rail thereon, a guard rail on said tie plate adjacent the main rail, means for engaging the outer portion of the foot flange of the guard rail, means for engaging the outer portion of the foot flange of the main rail, 80 and a rail brace having a rib formed thereon rising from said plate, and brace extending first upwardly between the foot flanges of said rails, then laterally into engagement with the top of the foot flange of the guard 85 rail, and then diagonally through the space between the rails and into engagement with the under side of the head of the main rail, substantially as described.

5. The combination of a tie plate, a main rail thereon, a guard rail on said tie plate adjacent the main rail, means for engaging the outer portion of the foot flange of the guard rail, means for engaging the outer portion of the foot flange of the main rail, 90 and a rail brace rising from said plate, said tie plate and rail brace being formed of a single piece of plate steel, the rail brace being first bent upwardly into engagement with the inner portion of the foot flange of 95 the guard rail, and then diagonally through the space between said rails and into engagement with the under side of the head of the main rail, substantially as described.

6. The combination of a tie plate, a main rail thereon, a guard rail on said tie plate adjacent the main rail, means for engaging the outer portion of the foot flange of the guard rail, means for engaging the outer portion of the foot flange of the main rail, 110 and a rail brace rising from said plate, said tie plate and rail brace being formed of a single piece of plate steel, the rail brace being first bent upwardly into engagement with the inner portion of the foot flange of 115 the guard rail, and then diagonally through the space between said rails, and into engagement with the main rail beneath the head thereof, the diagonal portion of the rail brace having one face pressed inwardly 120 and the opposite face pressed outwardly, to form a stiffening rib, substantially as described.

7. The combination of a tie plate, a main rail thereon, a guard rail on said tie plate adjacent the main rail, means for engaging the outer portion of the foot flange of the main rail, a shoulder formed on said plate and engaging the outer portion of the foot flange of the guard rail, and a rail brace 125

rising from said plate between the foot flanges of said rails, said brace engaging the inner portion of the foot flange of the guard rail, and also engaging the under side of the 5 head of the main rail, substantially as described.

8. The combination of a tie plate, a main rail thereon, a guard rail on said tie plate adjacent the main rail, a shoulder formed on 10 said plate and engaging the outer portion of the foot flange of the guard rail, means for engaging the outer portion of the foot flange of the main rail, and a rail brace rising from said plate, said brace extending first up-

wardly between the foot flanges of said rails, 15 then laterally into engagement with the top of the foot flange of the guard rail, and then diagonally through the space between the rails and into engagement with the under side of the head of the main rail, substantially as described. 20

In testimony whereof, we have hereunto affixed our signatures.
